BY H. W. Jenkins,
ATTORNEY.

UNITED STATES PATENT OFFICE.

CHARLES K. HALL, OF NEW ORLEANS, LOUISIANA, ASSIGNOR OF ONE-HALF TO E. J. HART, JR., OF SAME PLACE.

RECEPACLE FOR SHOT, &c.

SPECIFICATION forming part of Letters Patent No. 240,020, dated April 12, 1881.

Application filed September 18, 1880. (No model.)

To all whom it may concern:

Be it known that I, CHARLES K. HALL, a resident of the city of New Orleans, parish of Orleans, and State of Louisiana, have invented 5 a certain new and useful Improvement in Receptacles for Shot, &c.; and I do hereby declare the following to be a full, clear, and correct description of the same, reference being had to the annexed drawings, making a part 10 of this specification.

This invention relates to the construction of one or more receptacles for holding shot or any other dry substance which will roll readily, and in providing each with a delivery-tube, the said tube so connected as to be thrown up 15 in a vertical position when not in use, and the receptacles capable of being joined together, so as to form a series of the same with tubes pointing toward one common center. Its object is to save both time and labor in the 20 withdrawal, weighing, and putting up packages of shot.

On the drawings, Figure 1 represents a front view of a single receptacle, and Fig. 2 a side 25 view thereof. Fig. 3 represents internal and sectional views of a drum to which the delivery-tube is pivoted, and through which the shot passes from the receptacle to the same. Fig. 4 is a top view or plan of a number of receptacles connected, as will be hereinafter more 30 fully explained.

A A' are the sides of the receptacle, and B B' the front and rear thereof. Their corners are secured together by means of angle-pieces 35 c c', which are connected by screws or rivets, as desired.

To unite two or more receptacles, flat strips of metal, d, are placed over the vertical joints and secured to the front and rear plates by 40 means of screws or rivets, as shown in Fig. 4. The interior of each receptacle is furnished with an incline bottom, E, having a central valley of increased width and depth at its lowest point, as shown in dotted lines at Figs. 1 45 and 2. The front of each receptacle is provided with an opening communication with said valley, and over this opening is secured, through a rectangular tube, F, a drum, G, the latter formed in two sections, as at h i, one, 50 h, having an annular recess to receive the

outer edge of the projecting band k of the other section. Each section is provided with an inner flange, l m, with space sufficient between the band k to permit of the operating back and forth of a curved plate, n, having a circular 55 opening, over which the inner end of the delivery-tube x is permanently secured.

An opening corresponding in size with that in the curved plate is formed in the band k, as at o, so as to permit the shot to pass through 60 into the tube x when it is lowered to the position shown in dotted lines at Fig. 2 and in section at Fig. 3. The aforesaid tube is connected, by means of a yoke, P, and pivots q q', with the sides of the drum, as shown. In the 65 front portion of the yoke is suspended by means of hinges a plate, R, which, by reason of its lower edge resting on the projections s s' of the drum, serves to hold the same in a vertical position when not in use. The front 70 of this plate may, if so desired, bear the number of the shot in the receptacle.

The upper side of the tube F has its lowest portion open, as at t, to allow the shot remaining in the tube to run back into the same as 75 the tube is being brought into a vertical position.

The lower portion of the sides constitute the legs or supports of the receptacles. This portion may be made with openings in the same 80 or ornamented, as desired.

The receptacles being faced to one common center admits of a weighing-scale being placed within the said center, so that by swinging down the tube of any receptacle the shot from 85 the same will run directly into the said scale. When sufficient quantity has been weighed the attendant places his finger over the mouth of the tube, thereby stopping the discharge through the same. The bringing of the tube 90 into a vertical position causes the shot therein to run back into the drum, from which it passes out through the opening when next the delivery-tube is lowered.

Having described my invention, what I 95 claim as new, and desire to secure by Letters Patent, is—

1. A shot-receptacle provided with an inclined bottom, E, the lowest portion of which communicates with the internal tube, F, of a 100

drum, G, the latter provided with suitable openings and annular recess to admit of the operating of a delivery-tube, as described, and for the purpose set forth.

5 2. The combination herein shown and described of a series of shot-receptacles united by vertical plates *d*, and having their outer corners secured by angle-pieces *c*, each receptacle furnished with a delivery-tube, which

communicates through suitable openings in a drum, G, and its internal tube, F, with the said receptacle, for the purpose specified.

In testimony whereof I have hereunto signed my name.

CHAS. K. HALL.

In presence of—

A. B. ACKER,
J. W. HARDY.
